UNITED STATES PATENT OFFICE.

CHARLES A. BOWMAN, JR., OF PITTSBURGH, PENNSYLVANIA, ASSIGNOR TO TRINITY
COURT STUDIOS, OF PITTSBURGH, PENNSYLVANIA.

PHOTOGRAPHIC SERVICE-FLAG.

1,284,050.

Specification of Letters Patent.

Patented Nov. 5, 1918.

Application filed May 20, 1918. Serial No. 235,498.

To all whom it may concern:

Be it known that I, CHARLES A. BOWMAN, Jr., a citizen of the United States, residing at Pittsburgh, in the county of Allegheny and State of Pennsylvania, have invented 5 certain new and useful Improvements in Photographic Service-Flags, of which the following is a specification, reference being had therein to the accompanying drawing.

10 My invention has for its object to produce a photograph and a mount therefor having particular distinguishing characteristics, as to the photograph itself, and its embodiment with a supporting and surrounding base, 15 whereby to signify certain facts of military or naval service having a direct personal relation to the subject of the photograph.

The invention has in view to embody 20 within the border or confines of a "service flag" of the class represented in Design Patent No. 51,464 of Robert L. Queisser, a photographic representation, in star form, of the person corresponding to the star as a unitary member of the entire emblem.

25 Service flags of the kind referred to usually consist of a central rectangular field in white, surrounded by a red border, and provided with one or more stars. Ordinarily, these stars have no especial significance 30 other than a numerical one, and my invention has in view to invest each star with a personal, peculiar and immediately apparent self-evident value, in individualizing and vitalizing the star itself, and with particular reference to its mounting.

The essential point of my invention is the establishment of an individualized relationship between an individual and one of the numerically significant indicia, in this case 40 stars of five points. There may be a remote and sentimental significance too in accordance with the ancient custom or superstition of an individual choosing a particular star which throughout he might claim 45 as his particular guiding star through life, a custom perhaps referable back to the pagan idea of a particular god or tutelary deity, for each individual. Each star in the flag is assumed to have a fixed position and 50 each star in the flag stands for some individual. To emphasize this individuality of position and of personal relationship, I have devised a means of expressing such relationship by associating with each star some personal, peculiar, unalterable and inalien-

able characteristic of the person, so that the two are always together and must always be associated together in the minds of the public. The most strikingly peculiar and distinctive characteristic of an individual is 60 his face or a portrait of his face and this is what I use.

By this arrangement or combination of elements, the flag or other mounting indicates service; the star or stars the number 65 of persons serving; and the star-embodied picture represents the image of the server, typifying the personality, branch of the service, and rank, of the individual, together with such other incidents having to do with 70 such personal association as may be appropriately shown in the picture.

In my prior application filed March 14, 1918, Serial No. 222,473, I have shown and described my improved photographic print 75 and method of making the same, and the subject matter of the present application provides for the incorporation of such a photographic print, in star form, with a service flag, as a complete entity.

In making the photographic star, the particular object in view is to so combine the photographic representation with the star shaped outline and background, that when printed from the negative the well known 85 blue printing process or any other suitable photographic process capable of producing a blue picture, for reproducing prints from negatives, may be utilized. By this means I provide a composite print having a general 90 blue color, the surrounding background within the boundaries of the star being preferably of a deep uniform shade of blue, and with the photographic representation, as of a head or body or portion thereof, of 95 a lighter shade and in relief or contrast from the said background.

In making the complete picture I utilize the usual photographic method for making the negative which is then used in making 100 the print upon the sensitized paper or fabric or other suitable material, which may be then cut out in star form; or the print may be made in connection with the use of a "mask" whereby to protect the surrounding 105 sensitized surface so as to leave an outer surrounding body portion of white or approximately white color.

Either method may be employed, *i. e.*, the photographic star may be made separately 110

and separately attached to the white field of the service flag, or the field itself may be utilized as a printing base, in connection with suitable sizing and sensitizing material.

In the drawing, which illustrates one preferred embodiment of the invention, I show in face view a rectangular base of typical service flag form, provided with a photo-
graphic star.

Referring to the drawing, 2 represents the star base which may be of the regulation or arbitrary shape or form, but which is preferably made with the point portions of the star somewhat blunter than usual, whereby to provide a relatively large central body portion.

The portrait 3 preferably occupies such central position, either partly or entirely, and the device as thus made, confined within the edge portions of the star itself, provides the dark blue background referred to and the incorporated portrait or figure, 3, of the same general tint but somewhat in relief, whereby it is easily distinguished from the background.

The print as thus made constitutes a separate unit, having the arbitrary outline, embodying the portrait, and is mounted by printing, pasting, sewing or otherwise, upon the fabric constituting the white field 4 of the service flag, and within the surrounding red border 5.

If desired, the picture may be imprinted directly upon the field of the service flag in connection with the use of suitable sizing and sensitizing treatment.

It will also be understood that any desired number of individual photographic stars of the kind described may be embodied with a single flag, within the limitations of its field, and that their arrangement, location, size, shape, or other details may be varied within the taste and judgment of the designer without departing from the scope of the following claims.

It will be observed that while I show a five pointed star, I do not wish to be limited to five points as in some instances for religious or other reasons I may use a six pointed star or may even conceivably use some other figure. The portrait may be accompanied by other individualizing marks as for instance the signature, secret society mark or others.

In using the five pointed star I arrange the star with one of the points uppermost, and this arrangement aids to a certain extent in symmetrically positioning the portrait. I also carry the idea of emblematic 60 signification further. It will be remembered that the blue feature of the star of the Quesser design is preferably preserved in my structure, though modified in depth of tone to produce light and shade effects.

I carry this idea further, in case of death, the individualized star becomes golden, and in my flag the golden star is made to carry a golden color portrait. A similar effect may be produced when silver stars are used to 70 indicate wounded or otherwise incapacitated individuals.

I claim:—

1. In combination, a banner consisting of a red bordered white field with stars for individuals in said field, each of said stars bearing some indicia of a character unalterably related to the personality of the individual whom it represents, said star and indicia having color to indicate the vital condition of the particular individual associated therewith.

2. In combination, a service banner consisting of a red bordered white field service flag, blue portrait bearing stars in the said white field, individual golden portrait bearing stars for the dead, and individual silver portrait bearing stars for those disabled and incapacitated from further service.

In testimony whereof I hereunto affix my signature.

CHARLES A. BOWMAN, JR.
